**COMBINED ADJUSTABLE SUPPORT AND ULTRA-
SONIC TRANSDUCER HEAD FOR DIAGNOSTIC
SCANNERS**

Edward P. Meyer, Boulder, and William L. Wright, Longmont, Colo., assignors to Physionic Engineering, Inc., Longmont, Colo., a corporation of Colorado

Filed Dec. 26, 1963, Ser. No. 77,921

Term of patent 14 years

(Cl. D83—1)

FIG. 1 is a side elevation of a combined adjustable support and ultrasonic transducer head for diagnostic scanners showing our new design, the opposite side being substantially the same as the side shown;

FIG. 2 is a front elevation thereof;

FIG. 3 is a rear elevation thereof, with portions fragmentarily shown or omitted for convenience of illustration;

FIG. 4 is a top plan view thereof, with portions omitted for convenience of illustration; and,

FIG. 5 is a cross-section taken on line 5—5 of FIG. 1. We claim:

The ornamental design for the combined adjustable support and ultrasonic transducer head for diagnostic scanners, as shown and described.
